Design No. 14,991, dated May 6, 1884.

UNITED STATES PATENT OFFICE.

L. LUM SMITH, OF PHILADELPHIA, PENNSYLVANIA.

DESIGN FOR THE BACK OF A GAME-CARD.

SPECIFICATION forming part of Design No. 14,991, dated May 6, 1884.

Application filed March 24, 1884. Term of patent 3½ years.

To all whom it may concern:

Be it known that I, L. LUM SMITH, a citizen of the United States, residing in Philadelphia, in the State of Pennsylvania, have invented and produced a new and original Design for the Backs of Game-Cards, of which design the following is a specification.

The annexed engraving, forming part hereof, represents said design, which consists of a pictorial combination, the central and leading feature of which is a medallion picture of the Presidential Mansion, or White House, within a circular border, upon which, in a sitting position, there is an American eagle grasping in its talons arrows and an olive branch. Above the eagle there is an arch of thirteen stars. Projecting up upon either side of the eagle are American flags, which are partly concealed

by said medallion. The medallion rests on an American shield. 20

The groundwork of the design consists of small geometric figures of irregular shape in juxtaposition producing a mosaic, mottled, or watered effect. 25

I claim—

For the backs of game-cards, the design consisting of a central medallion resting on a shield and supporting an eagle below an arch of stars, with flags arranged in combination on a mottled ground within an oblong border 30 or frame, substantially as shown and described.

L. LUM SMITH.
